UNITED STATES PATENT OFFICE.

LOUIS KESSLER, OF CHICAGO, ILLINOIS.

AIR AND GAS ENGINE.

1,042,560.

Specification of Letters Patent.

Patented Oct. 29, 1912.

Application filed February 11, 1911. Serial No. 607,917.

To all whom it may concern:

Be it known that I, LOUIS KESSLER, a citizen of the United States, residing at Chicago, in the county of Cook and State of Illinois, have invented certain new and useful Improvements in Air and Gas Engines, of which the following is a specification.

My invention relates to improvements in air and gas engines, and has for its object 10 the provision of means for increasing the efficiency of such engines.

The class of engines to which my present invention is especially applicable are known as hot air engines, and my invention consists in providing means for and supplying to such engines a small quantity of such a material as will render the gaseous contents of the cylinder more sensitive to the changes of temperature.

20 I attain these objects by the mechanism illustrated in the accompanying drawing, in which—

Figure 1 is a side elevation of the motor or engine with my present invention applied thereto; Fig. 2 is a plan of the structure shown in Fig. 1; Fig. 3 is a central longitudinal section of the mechanically operated relief valve; Fig. 4 is a longitudinal central section of the mechanism shown in Figs. 1 and 2; Fig. 5 is a section of the valve in the passage leading from the cylinder to the furnace; Fig. 6 is a section of the tight fitting piston with the connecting rod attached, and Fig. 7 is a side elevation, partially in 35 section, of the means for supplying the mixture to the cylinder.

Similar reference numerals refer to similar parts throughout the several views.

The motor is mounted on a convenient base, 1, of suitable size, longitudinally of which are bolted parallel brackets, 2, which are braced by suitable cross bars or bolts, 3, and have extending vertically from each end and approximately the center, risers 5, 11 and 12. The tops of the right hand or rear pair of risers, 5, are provided with suitable alining bearings, 6, for the ends of a crank shaft, 7. The crank of the crank shaft is disposed between the bearings, 6, and upon the ends of the shaft which extend beyond each bearing are disposed fly wheels, 8. A grooved pulley, 9, is mounted upon the shaft, 7, outside one of the fly wheels, and a crank bolt, 10, projects laterally from a spoke of the opposite fly wheel for purposes 55 to be described hereinafter.

Mounted between the intermediate and front risers, 11 and 12, and supported thereby, is a cylinder, 13, having radiating cooling flanges, 14, extending therefrom. A piston, 15, having a central passage 17 extending longitudinally thereof, is mounted in said cylinder, 13, and is connected with the crank, 7, by a yoked or bifurcated connecting rod, 16, the two ends of which are pivoted to the rear or outer end of the piston upon each side of the center thereof.

60 Alining bearings 18 are provided in the brackets, 2, between the risers, 5 and 11, in which is mounted a rocker shaft, 19. From 70 the left hand end of this rocker shaft, extends upwardly an arm, 21, the upper end of which is connected by a link 22, with the crank bolt, 10, of the left-hand fly wheel. A suitable oil cup, 23, is located upon the 75 cylinder near the base thereof for lubricating the piston 15.

To the head or rear end of the cylinder, 13, is secured a tube, 24, the interior of which is practically a continuation of the 80 inner walls of the cylinder 13. The diameter or bore of the cylinder is enlarged at 13^a for a short distance from its point of connection with the tube 24 and a collar, 24^a, which extends inwardly and serves to 85 reduce the bore at their junctures, is interposed between their meeting edges. The outer end of the tube, 24, is closed by a suitable cap plate, 24^b, from which, along the axis of the tube, extends a rod 25, one end 90 of which is fixed in the cap, 24^b. Mounted within the remote end of the tube, 24, is an annular collar, 4. Mounted to slide upon the rod, 25, is a closed hollow cylindrical plunger, 26, which is of slightly smaller 95 diameter than the bore of the collar, 4, and has a central chamber, 27, extending from its outer end to a point near its inner end, for the reception of the rod, 25. The diameter of the plunger, 26, is such as to leave 100 but a small clearance between it and the inner walls of the collars 4 and 24^b. From the inner or rear end of the cylindrical plunger, 26, a rod, 28, extends through the central passage in the piston, 15, and into 105 the rear end of said rod, is screwed a nut, 29, the outer end of which has pivotally connected therewith one end of a link, 30, the other end of which is pivoted to the upper end of the arm, 20, which is fixed upon the 110 rocker shaft, 19, which latter connects, as before described, with the crank shaft, 7,

through the arm, 21, link, 22, and left hand fly wheel, 8. The arm, 20, and link, 30, move between the bifurcated or yoked portion of the connecting rod, 16. A passage leads from the forward portion of the cylinder, 13, through the cylinder wall, and to the outer end of this passage is secured a tubular valve casing, 32, in the upper portion of which is an outlet valve, 34, to which is connected the lamp to be hereafter described. About the remote or outer end of the tube, 24, is provided a casing forming a heating chamber, 35, and under the lower end of this casing is fixed a suitable lamp or furnace, 36. A tube, 37, running from the casing, 32, above the outlet valve, 34, to the furnace, 36, utilizes such exhaust as there is to force the draft of the furnace and also serves to relieve such pressure as develops when the piston and plunger approach each other. The connection of the piston, 15, with the crank shaft 7, and the plunger, 26, with the arms, 20 and 21, links, 22, and 30, and left hand fly wheel is such that the plunger, 26, precedes the piston, 15, by a quarter of a turn of the shaft, or has a lead of half of the distance through which said plunger reciprocates, and the plunger is so proportioned as to length that the paths of reciprocation of the piston and plunger coincide through approximately half their extent and the plunger comes closely adjacent to the piston at the end of its inward or crankward stroke.

It will now be seen that when the piston 15 has proceeded half of its outward stroke, the plunger, 26, has reached the outer or remote end of the tube 24, and has entered the collar, 4. As the piston completes its outward movement the plunger travels backwardly one half its stroke. When the stroke of the piston toward the crank shaft is completed, the plunger has completed its journey toward the crank shaft and has already moved half of its journey toward the outer or hot end of the tube.

Upon the upper side of the head of the cylinder, 13, is an internally threaded depression into which is screwed the base of a suitable cup, 39, which has been threaded for that purpose. The top of the cup is internally threaded and is closed by a cap, 40, having an exteriorly threaded flange, 41, to engage with the thread in the cup. Just below the threading upon the upper part of the cup is a passage-way, 42, leading therefrom. This passage-way is led by tubing, 43, to a needle valve casing, 44, in which is a vertically located needle valve, 45. From beneath the valve, 45, and leading therefrom, is a horizontal passage-way, 46, which terminates in a vertical passage, 47. The vertical passage, 47, is continued downwardly through the port, 47^a, to the atmosphere, and in the upper end thereof is mounted a

gravity seating valve, 48, which closes said passage against a downward flow. From above the valve, 48, the passage-way is carried by tubing, 49, to a channel, 18, running into the outer end of the tube, 24, beyond the collar, 4.

At a point approximately at which the piston, 15, and plunger, 26, come closest together, I provide a passage-way 50, leading into the cylinder, 13. Into the outer end of this passage-way is screwed a valve casing, 51, from the valve chamber, 52, in which extends a valve stem, 53, backwardly toward the crank shaft, 7.

Upon the valve stem, 53, is mounted a valve, 54, from back of which is a port, 55, leading to the atmosphere. The valve 54, is maintained normally closed by an expansion spring, 56, coiled about the valve stem, 53, and extending between the valve casing, 51, and a collar, 57, secured to the valve stem. Mounted upon the crank shaft, 7, opposite the end of the valve stem and in operative proximity thereto is a cam disk, 58.

In the cup, 39, I place a solution of chlorid of lime which will slowly give off chlorin fumes. The needle valve, 45, is opened which will permit the fumes to pass from the cup, 39, through the tubing, 43, to the horizontal passage-way 46.

When the pressure inside the cylinder 13 and tube, 24, is reduced below that of the atmosphere, air passes from the atmosphere through the port, 47^a, lifting the valve, 48, 100 and passing therethrough and through the tubing, 49, and channel, 18, to the interior of the tube, 24, but in so doing it also carries some of the chlorin fumes which have descended through the needle valve, 45, to the horizontal passage-way 46.

I find that when a gaseous mixture, such as above described, is fed to the engine, it is desirable to positively relieve the pressure which develops between the piston, 15, and plunger, 26, and for that purpose I have provided the valve, 54, and its actuating mechanism as above described.

Having thus described my invention, what I claim as new and desire to secure by Letters Patent, is:—

1. In a hot air engine having a cylinder, a tight fitting piston mounted therein, a loose fitting displacing piston also mounted therein, an inlet port in said cylinder, a valve casing connected therewith, a gas generator connected with said casing, and an atmospheric port also connected with said casing whereby gas and atmospheric air are drawn into said cylinder.

2. In a hot air engine having a cylinder, a tight fitting piston mounted therein, a loose fitting displacing piston also mounted therein, an inlet port in said cylinder, a valve casing connected therewith, a gas gen-

- erator connected with said casing, an atmospheric port also connected with said casing, an independent outlet port, a valve for controlling same, and means for mechanically 5 operating said last mentioned valve.
3. A motor comprising a cylinder, a tight fitting piston mounted therein, a loose fitting piston, also mounted therein, means for synchronizing the movement of said pistons, 10 a gas generator, and means for admitting a mixture of gases to said cylinder.
4. A motor comprising a cylinder, a tight fitting piston mounted therein, a loose fitting piston also mounted therein, the said cylinder having different bores at different portions of the path of reciprocation of said last mentioned piston, means for synchronizing the movement of said pistons, a gas 15 generator, and means for admitting a mixture of gases to said cylinder.
5. A motor comprising a cylinder, a tight fitting piston mounted therein, a loose fitting piston also mounted therein, means for synchronizing the movement of said pistons, 20 means for heating one end of said cylinder, a gas generator, and means for admitting a mixture of gases to said cylinder.
6. A motor comprising a cylinder, a tight fitting piston mounted therein, a loose fitting piston also mounted therein, means for synchronizing the movement of said pistons, 25 an inlet port to said cylinder, a gas generator, and means for mixing the gas from said generator with air and for admitting 30 the mixture of gases to said cylinder.
7. A motor comprising a cylinder, a tight fitting piston mounted therein, a loose fitting piston also mounted therein, means for synchronizing the movement of said pistons, 35 inlet and outlet ports for said cylinder, a furnace for heating one end of said cylinder, means for connecting said port with the furnace and for supplying pressure to said 40 furnace.
- 45 8. A motor comprising two alining cylinders, a collar interposed between said cylinders, a tight fitting piston mounted in

one of said cylinders, a loose piston reciprocating in both of said cylinders, means for synchronizing the movement of said 50 pistons, means for heating one end of one of said cylinders and means for associating the exhaust port of the cylinder with heating means.

9. A motor comprising two alining cylinders, a collar having a smaller bore interposed between said cylinders, one of said cylinders being counterbored adjacent to said collar, a tight fitting piston mounted in said counterbored cylinder, a loose piston reciprocating in both of said cylinders, means for synchronizing the movement of said 60 pistons, and means for heating one end of one of said cylinders.

10. A motor comprising two alining cylinders, a collar having a smaller bore interposed between said cylinders, one of said cylinders being counterbored adjacent to said collar, a tight fitting piston mounted in said counterbored cylinder, a loose piston 70 reciprocating in both of said cylinders, means for synchronizing the movement of said pistons, and means for heating the remote end of the cylinder which is not counterbored.

11. A motor comprising a cylinder, a piston mounted therein, another cylinder, a plunger, means for synchronizing said piston and plunger to cause said piston to reciprocate wholly within said first mentioned cylinder and said plunger to reciprocate in both of said cylinders, areas of reduced cross section near the ends of the path of reciprocation of said plunger, and an area of enlarged bore between the reduced area at one end of the path of reciprocation of said plunger and the path of reciprocation of said piston.

In testimony whereof I affix my signature in the presence of two witnesses.

LOUIS KESSLER.
